PRESELECTING TOOL FOR TELETYPEWRITERS

Harold W. Billard, Hempstead, and Edgar C. Brundage, New Brighton, N. Y., assignors to Western Electric Company, Incorporated, New York, N. Y., a corporation of New York

Application June 22, 1951, Serial No. 233,093

4 Claims. (Cl. 178—1)

1

This invention relates to tools for use in adjusting and repairing signalling apparatus and more particularly teletypewriters.

There are two general types of teletypewriters, one wherein the message is printed on a tape while in the other it is printed on a page taken from a roll of sheet material. In each machine there are selecting mechanisms which when functioning properly will select letters, numbers, or characters for printing or will perform other functions of the teletypewriter, such as shifting of the carriage. In each selecting mechanism T-levers are employed, although in one type of machine the T-levers, normally responding to the marking and spacing pulses, act directly on permutation or code bars, the T-levers in the other machine actuate selector vanes which operate their respective bell crank levers to shift the code bars to bring about the desired functions.

In the past to repair or adjust teletypewriters it was necessary for the various parts of the selecting mechanisms to be operated by manually moving the selector magnet armature, the transfer levers, the cam-operated bell crank levers, the T-levers, and the code bars including in one machine also the selector vanes and their respective bell crank levers operating the code bars. The accuracy of the movement of these parts distances comparable to their distances of movement in actual operation and the adjustments required, depends upon the experience and ingenuity of the individuals.

An object of the invention is to provide a tool which is small in size, readily attachable to teletypewriters and highly efficient for actuation to operate the selector mechanisms to perform all the operating functions of the teletypewriter.

With this and other objects in view the invention comprises a tool for use in adjusting and repairing teletypewriters wherein mechanisms include pivotally supported T-levers actuatable singly and in varied combinations to select any of the operating functions of the teletypewriters, the tool including a support removably attachable to the teletypewriter and provided with selective levers pivotally carried by the support and arranged so that they will engage their respective T-levers and operate them to carry out all of the operating functions of the teletypewriter.

Other objects and advantages will be apparent from the following detailed description wherein:

Fig. 1 is a top plan view of the tool;

Fig. 2 is a side elevational view of the tool with one of the levers operated, portions of the tool being shown in section;

2

Fig. 3 is a sectional view taken along the line 3—3 of Fig. 1 with certain of the levers operated;

Fig. 4 is a fragmentary sectional view of a teletypewriter with the tool mounted thereon;

Fig. 5 is a view of the mechanism shown in Fig. 4 with one of the levers of the tool operated; and

Fig. 6 is a fragmentary sectional view of another form of teletypewriter illustrating the tool mounted thereon.

Referring now to the drawings, attention is first directed to Figs. 1 to 3 inclusive which illustrate the tool as having a support 100 connected to an auxiliary member 101 by the aid of a screw 102 extending through spacers 103 and intermediate washers 104.

The opposing end of the support 100 is provided with a threaded aperture 106 to receive a stud 107 which extends through aligned apertures of the spacers 103 and the auxiliary support 100. The stud 107 acts as a pivot for five selective levers 111, 112, 113, 114, and 115. Through the aid of a lock washer 116 and a thumb nut 117 on the outer threaded end of the stud 107, the support 100 and the auxiliary support 101 may be forced toward each other tending to clamp the levers and their spacers in close engagement with each other, creating frictional forces capable of holding the selective levers in any position but not to interfere with the manual actuators thereof.

The ends of the levers adjacent the pivot or stud 107 are identical in structure, they being provided with the projections 118 as illustrated in Fig. 3. The other ends of the levers are similar in contour but variable in length so that their handles 120 will be disposed in staggered relation with respect to each other as illustrated in Fig. 1. The handles in the present embodiment of the invention bear numerals 1, 2, 3, 4, and 5 to identify the levers 111 to 115, inclusive.

The tool is provided with thumb nuts 122 normally held against displacement by a bracket 123 which is fixed to the support 100 and provided with split apertured ends 124 to receive the reduced ends. Furthermore, the support 100 is apertured in any suitable manner to receive mounting studs of teletypewriters so that through the aid of the thumb nuts 122 the tool may be removably secured to the teletypewriter.

Attention is now directed to Sheet 2 of the drawings, illustrating Figs. 4 and 5. These figures are enlarged fragmentary illustrations of one species of teletypewriter shown in Fig. 7 of the patent to Morton et al., 1,745,633. The two

digit numbers identifying parts of the teletypewriter are identical with the reference numerals found in Fig. 7 of the above patent. In the selecting mechanism shown, the bell crank lever 17 is cam-operated to act upon the selecting finger 12 which normally controls the T-lever 31 and its respective permutation or code bar 38. There are five sets of selecting mechanisms, leading to five code bars 38, which include T-levers 37 spaced from each other on a common pivot 42 distances similar to the spacing of the selective levers 111 to 115 inclusive of the tool.

The permutation or code bars 38 may be shifted from one position to another controlled by elongate apertures 41 receiving a pin 39. The code bars are notched along their inner surfaces, the notches being so arranged that the actuation of the T-levers 37, singly and in varied combinations, will result in aligning given groups of notches to permit actuation of various mechanisms to bring about certain functions of the machine including printing of any of the letters, numbers, or characters. The T-levers 31 are disposed in a given order so that when the tool is mounted on the machine through the securing of the thumb nuts 122 to conventional studs 14 of the teletypewriter, it will be known that the selective levers will be positioned to actuate any one of the known T-levers. For example, when the operator moves the selective lever with a handle bearing the number 1, he will know that the top T-lever of the selecting mechanism of the teletypewriter has been operated. The code system for each teletypewriter is known by the repair man and, if not known, a chart bearing the code may be present before him. The operator may then, through the aid of the tool, move the selecting mechanisms through their operating cycles to carry out every function of the teletypewriter, watching the movement of the various parts and making the necessary adjustments.

The species of teletypewriters shown in Fig. 6 is of the page printing type shown in the patent to S. Morton et al., 1,904,164. The tool is illustrated as being mounted on studs 17 and 18 in Fig. 28 of this patent. The two digit numbers in Fig. 6 correspond with the reference numerals in Fig. 28 of the last mentioned Morton et al. patent. In this structure it will be apparent that the T-levers 29 are mounted on a common pivot 31 in spaced positions corresponding to the spacing of the selecting levers 111 to 115 inclusive so that when the tool is mounted on the teletypewriter as shown, the ends 118 of the selective levers will engage their respective T-levers 29. In this species of teletypewriter the T-levers are definite parts of the selective mechanisms although they do not act directly on the permutation or code bars, their actuations being translated to the code bars through selector vanes and bell crank levers as shown in Fig. 1 of the above patent.

With either species of the teletypewriter the tool, which is normally approximately half the size shown in Fig. 1, may be readily carried by the person designated to repair or adjust the teletypewriters, the tool being ready at all times for mounting on either species of teletypewriters. Furthermore, the moment the tool is mounted in place, its selective levers are automatically positioned with respect to the T-levers of the selective mechanisms of the machines to be adjusted or repaired. By actuating the selective levers 111 to 115, inclusive, singly and in their varied combinations, the operator may observe the actions

of all of the parts of the teletypewriter including the selecting mechanisms and the printing mechanisms and make any adjustments which may be needed. When their adjustments have been completed, the tool may be readily removed from the teletypewriter and transported to another needing repair.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. A tool for use in adjusting and repairing teletypewriters wherein means are embodied to operate pivotally supported T-levers to actuate mechanisms singly and in varied combinations to select any of the operating functions of the teletypewriters, the tool comprising a support, means to removably secure the support to a teletypewriter adjacent the T-levers, and selective levers pivotally carried by the support and positioned to engage and actuate their respective T-levers independently of said means to operate them whereby said mechanisms will be actuated at any desired speed to select any of the operating functions of the teletypewriter by movement of the selecting levers singly and in varied combinations to actuate the T-levers of the said mechanisms.

2. A tool for use in adjusting and repairing teletypewriters wherein means are embodied to operate pivotally supported T-levers to actuate mechanisms singly and in varied combinations to select any of the operating functions of the teletypewriters, the tool comprising a support, means to removably secure the support to a teletypewriter adjacent the T-levers, selective levers pivotally carried by the support and positioned to engage their respective T-levers, and handles for the selective levers marked to identify them and their respective T-levers whereby the mechanisms may be actuated at any desired speed to perform any of the functions of the teletypewriter by movement of the selective levers by the aid of their handles singly and in varied combinations to actuate the T-levers of the said mechanisms independently of said means to operate them.

3. A tool for use in adjusting and repairing teletypewriters wherein means are embodied to operate pivotally supported T-levers to actuate mechanisms singly and in varied combinations to select any of the operating functions of the teletypewriters, the tool comprising a support, means to removably secure the support to a teletypewriter adjacent the T-levers, selective levers pivotally carried by the support and positioned to engage their respective T-levers, spacers interposed between the selective levers to locate them in like planes with their T-levers, and handles for the selective levers marked to identify them and their respective T-levers whereby the mechanisms may be actuated at any desired speed to perform any of the functions of the teletypewriter by movement of the selective levers by the aid of their handles singly and in varied combinations to actuate the T-levers of the said mechanisms independently of said means to operate them.

4. A tool for use in adjusting and repairing teletypewriters wherein means are embodied to operate pivotally supported T-levers to actuate mechanisms singly and in varied combinations to select any of the operating functions of the tele-

typewriters, the tool comprising a support, means to removably secure the support to a teletypewriter adjacent the T-levers, selective levers pivotally carried by the support and positioned to engage and actuate their respective T-levers whereby actuation of the said mechanisms will be actuated at any desired speed to select any of the operating functions of the teletypewriter by movement of the selecting levers singly and in varied combinations to actuate the T-levers of the 10 said mechanisms independently of said means to

operate them, and means applying a holding force to each of the selecting levers to hold them and the mechanisms including their T-levers in operated positions.
